(Cl. D52—10)

FIG. 1

FIG. 2

FIG. 3

FIG. 4

FIG. 5

FIG. 6

FIG. 1 is a front perspective view of the beam balance weighing scale, showing my design;

FIG. 2 is a front elevational view;

FIG. 3 is a left end elevational view with the trays removed, the right end of the scale being a mirror image of the left end, except that it lacks the wire loop projecting from the front of the scale body as seen in FIGS. 1 and 3;

FIG. 4 is a top plan view of the scale with the trays removed;

FIG. 5 is a bottom plan view; and

FIG. 6 is a rear elevational view with the trays removed.

I claim:

The ornamental design for a beam balance weighing scale, as shown and described.
